UNITED STATES PATENT OFFICE.

DANIEL E. WOODHULL, OF NEW YORK, N. Y., ASSIGNOR TO AMERICAN BANK NOTE COMPANY, A CORPORATION OF NEW YORK.

METHOD OR ART OF MAKING PLATES FOR PRINTING SAFETY TINTS.

Application filed July 15, 1921. Serial No. 485,032.

To all whom it may concern:

Be it known that I, DANIEL E. WOODHULL, a citizen of the United States, residing at the borough of Manhattan, in the city, 5 county, and State of New York, have invented certain new and useful Improvements in the Method or Art of Making Plates for Printing Safety Tints, of which the following is a specification, reference being 10 had therein to the accompanying drawings, which form a part thereof.

My invention relates to the method or art of making plates for printing safety tints, and more particularly to a method or art 15 practiced in part mechanically, in part manually, in part photographically and in part chemically.

The method of producing plates for making safety tints, employed prior to my invention consisted in combining different portion 20 of a geometrical or scroll line design produced by means of a rose engine or pantograph, and reproducing the design thus formed by ordinary photo-engraving methods so as to produce either a cameo or intaglio printing surface, using a single plate 25 containing the entire design, or a plurality of plates each containing only a portion thereof, according to whether the plates were 30 to be used in multicolor or single color work.

Tint designs are formed of fine lines closely juxtaposed, the design being created by the formation of loops or convolutions 35 crossing and recrossing each other and grouped about a common center so that notwithstanding the lines are all of the same breadth, different tonal effects are secured in different parts of the design by reason of closer proximity of the line in adjacent loops 40 and a common crossing point of a great number of lines. Such designs are solely mechanical in their origin, and so appear to workers in the art.

While designs of this character are intricate and, when impressed upon bank notes 45 or negotiable instruments, impart a large factor of safety thereto, they may be exactly reproduced mechanically by one skilled in the use of a rose engine or pantograph.

By reason of the fineness of the line and the methods of reproduction heretofore employed, it has been found impossible to produce printing plates by a practical method 50 in which the mechanical aspects of the de-

sign may be eliminated or modified in a 55 manner to make counterfeiting thereof difficult or impossible. When multicolor work has been resorted to in order to increase the difficulties of reproducing such designs, it has been necessary to use plates wherein all 60 adjacent lines of a group will be of the same color, the plates used for one color having blank spaces corresponding with the portions of the plate bearing portions of the line design to be inked in another color. 65 While wide divergence in the color scheme of multicolor prints has heretofore been possible, the method of making the printing plates heretofore employed has placed great 70 limitations as to the distribution of colors throughout the imprint.

To secure the desired effect of the imprint, absolute register of the plates for different colors is essential, since one of the requisites of safety tint work is a perfection of execution which will make reproduction difficult. 75

With the above conditions in mind, I have devised a method of producing plates of this character whereby the uniformity of the thickness of the lines of the design, which 80 is a characteristic of line designs created by a rose engine or pantograph, may be varied in arbitrarily selected portions of the design so as to preclude the reproduction of the design mechanically. The method of my 85 invention also contemplates the eradication from the plate of other essential characteristics of machine-made design and if necessary the substitution therefor of arbitrary figures, if desired, which figures could not 90 possibly be mechanically incorporated in a design.

The method of my invention is particularly adapted to the making of plates for multicolor safety tints which will permit the 95 use of different colors promiscuously in lines distributed throughout the completed design, even though positioned only a few thousandths of an inch away from lines of other colors, which condition can be secured only by the proper preparation of the plates for different colors, and can be secured only by the exercise of the highest skill, and with the aid of machinery in making the impression, of a complicated and expensive 100 nature, and beyond the means of the ordinary counterfeiter.

By means of plates made in accordance

with the method or art of my invention, all restrictions as to the distribution of the inks of different colors are avoided, and the color scheme is controlled primarily by the 5 plates.

In making plates for multicolor tints, closely adjacent lines as they appear in the tint impression may be accurately positioned upon different plates, and many of 10 those difficulties incident to the securing of perfect register may be avoided. A series of color plates may thus be made wherein the different colors instead of being in isolated parts of the print may be distributed throughout the print in such close juxtaposition one to the other as to make unauthorized reproduction practically impossible.

The method of making the plates, 20 permits the strengthening of the line thereof as well as arbitrary variations in their widths, and the incorporation of arbitrary figures in the design.

The invention consists primarily in the 25 method or art of making plates for printing safety tints consisting in mechanically creating a line geometrical design, photographically enlarging said design, modifying the characteristics of some lines in said 30 design, whereby such lines are readily distinguishable from the mechanically produced lines, photographically reducing the modified design, and making a photo-engraving of the reduced design; and in such 35 other novel steps and practices as are hereinafter set forth and described, and more particularly pointed out in the claims hereunto appended.

Referring to the drawings, 40 Fig. 1 is a view of a fragmentary portion of a geometrical design to be used in making plates in accordance with the method or art of my invention;

Fig. 2 is a photographic enlargement of 45 said portion of the design,

Fig. 3 is a view thereof, some of the lines being manually modified and others being blocked out,

Figs. 4, 5 and 6 are views similar to Fig. 50 3 forming therewith a group of plates for multicolor work; and

Figs. 7, 8, 9 and 10 are photo-engraved 55 reproductions of the modified figures shown in Figs. 3, 4, 5 and 6.

Like letters refer to like parts throughout the several views.

In the practice of the method or art of 60 my invention, an original, line, geometrical design is created by means of an ordinary rose engine or pantograph so set as to cause the production of this design upon a reduced scale while preserving the proper relative spacing between succeeding loops or convolutions and uniform width of the continuous line of which the design is formed.

This design results from the formation of a sequence of convolutions or loops, the lines of succeeding loops being spaced closely together by a relative step-by-step movement of the plate on which a design is impressed 70 and the working point acting thereon. The opposite lines of each loop are grouped about a common center so that the portions thereof toward the center cross and re-cross the lines of preceding and succeeding loops 75 and the spaces between the lines are varied so as to give different tonal effects in the design without variance in the width of the lines themselves. By adjustments in the machine, a solid tone in some portions 80 of the design may be secured.

The tonal effects and the general contour of the design may be varied indefinitely, but such variations are the results of functionings in the machine and wherever distinct lines appear in the design, they 85 will all be of uniform width.

Such designs are created upon a glass plate surfaced so as to be impenetrable to light rays, the working point removing this 90 surfacing so as to produce what is the substantial equivalent of a photographic negative. Fig. 1 of the drawings represents such a plate, and its scale approximates the 95 actual dimensions of an original design.

From a reference to Fig. 1, it will be noted that the spacing between the lines is very small, and that if portions of the 100 design be repeated a number of times in building up a completed design of the desired dimensions, and if it be desire to modify or delete or segregate any of these lines, it will be practically impossible, or very difficult, to do so, since it would be necessary to do the work by hand and the 105 fineness of the lines and their close proximity to each other would inevitably lead to the running together of the lines, loss of definition in each line, and an uncontrollable variance in the thickness of the 110 lines.

By the old methods, the negative-like plate was used as in photo-engraving, to reproduce the design upon a metal plate containing a resist and a sensitized emulsion, which plate after being developed is acid-etched as in photo-engraving. Hence the original design was necessarily created to scale and could not be made upon an enlarged 115 scale and then reduced, since this would 120 destroy the relative thickness of lines and spacing of succeeding convolutions.

In the practice of the method or art of 125 my invention, in order to permit modification in the width of some of the lines, removal or deletion of some of the lines to vary the tonal effects and the formation of a plurality of plates each including some only of the lines, as in multi-color work, 130 which would entail the removal of some

lines in some plates and their retention in other plates, I first enlarge the original design by ordinary photographic methods such as solar or bromide printing, such an enlargement being shown in Fig. 2 of the drawings, and being a positive enlarged print upon paper. From this enlargement a photographic negative is made, which after being properly developed is used in making photographic imprints upon a plurality of rigid metal plates having an affinity for ink. The design must be placed in exactly the same position upon each of these metal plates. Such plates are shown in Figs. 3 to 6 of the drawings.

A plurality of plates is used when multi-color work is to be done therewith, exactitude in the placing of the design being necessary since when the design has been completely produced the portions of the design appearing on each plate must exactly register with the portions of the design upon each of the other plates so that the impression from the printing plates made therefrom, either simultaneously or successively, will exactly reproduce the completed design, and such modifications incorporated therein as will be more particularly referred to.

The rigidity of the metal plates will avoid any possible variation in the dimensions of the design while work is being done thereon, and will greatly facilitate accuracy in making photographic reproductions thereof upon a reduced scale during a further stage in the method or art. In the accompanying drawings the glass plate upon which the original design is placed is indicated at A, and the photographic enlargement thereof shown in Fig. 2 at B. The metal plates shown in Figs. 3 to 6 are indicated at C, D, E and F respectively, while the final master printing plates shown in Figs. 7 to 10 are indicated at G, H, I and J.

Since the invention relates only to the production of the printing plates, a reproduction of the print in different colors is not shown in the drawings, a black and white reproduction being inadequate to give any conception of the effects secured by means of plates made in accordance with the invention.

In the further description of the invention, it will be assumed that it is desired to produce cameo printing plates for multi-color work, and that four plates are required, the number of plates, however, placing no limitation upon the number of colors employed.

In photographic enlargement work, where the subject may be increased ten-fold in size, there is a loss of definition in the reproduction and any imperfections are greatly exaggerated. Hence in the print B and the photographic reproduction there-

of upon the plates C, D, E and F all imperfections and irregularities in the lines of the design will be clearly apparent since these lines instead of being hair lines will, by the process of enlargement, have attained a width of possibly a sixteenth of an inch or greater, and instead of being spaced apart a few hundredths or a few thousandths of an inch, will be spaced apart a quarter or a few hundredths of an inch or possibly even more in some portions of the design. Toward the center of the design what appears in the original as a deep tone, appears in the photographic enlargement as a ragged, irregular conglomeration of lines. The opposite edges of each line will also appear somewhat ragged and the lines may be broken in spots. These imperfections will appear in the reproduction upon the plates C, D, E and F.

While the design is made from a continuous line subject to the imperfections above noted, and of uniform width, in describing the modification of the design, the lines of succeeding loops will be referred to, and reference will be had to four of these loops, it being understood that the same practices may be employed throughout the entire design.

The first line of the loops in a group of four such loops is indicated in each of the figures at a, b, c and d, while the final lines of said loops are indicated at a', b', c' and d'. Assuming that each of the plates C, D, E and F are to be used for one color only, and that the lines a—a' of each group of four loops making the completed design are to appear in one color; the lines b—b' in another color; the lines c—c' in a third color, and the lines d—d' in a fourth color, and that it is desired to have the lines a—c of greater width than the lines a'—c', or the lines b and d, and the lines b' and d' of greater width than the lines a' and c', the first step consists in blocking out the lines b—b', c—c' and d—d' upon the plate C by means of a brush and in a color which will readily reflect light rays. This will leave upon the plate C only the lines a—a' of each group of four loops. When the other lines have been thus deleted, the operator by means of a fine brush and a black ink will increase the width of each line a, there being sufficient space to permit a material increase in the width of this line and still provide sufficient space between it and the line b' which will appear in the imprint in a different color. The increase in the line may be regular or uniform, or may be irregular or graduated, as desired. The line a' may be strengthened by a retouching process.

The plate D is then remodeled in a similar manner, all lines b—b' being retained on this plate, and being retouched, or broad-

ened, or both, as desired, the lines $a-a'$, $c-c'$ and $d-d'$ being deleted.

The plate E is then modified in the same manner as to the lines $c-c'$, and the lines 5 $a-a'$, $b-b'$ and $d-d'$ deleted.

The same process is then followed with the plate F, the lines $d-d'$ of the loops of each group being retained and the lines 10 $a-a'$, $b-b'$ and $c-c'$ being deleted.

10 When this work is completed, it will be observed that a composite reproduction of the four plates C, D, E and F will consist of the original design shown upon the enlargement B with certain selected lines

15 widened and all lines sharply defined so as to ensure perfect, clearcut, continuous lines in the printing plate subsequently made from these plates.

The deeper toned portions of the design

20 indicated at e , Figs. 1 and 2 of the drawings, preclude any substantial modifications of the lines, as such, in this portion of the design. It is possible, however, by the use

25 of a brush and white or black inks to delete some portion of the design and to strengthen other portions thereof so that the original character of the machine-made design as to this portion thereof may be so modified as to make it readily distinguishable from

30 designs produced by means of the rose engine or pantograph. Also by use of the brush and black or white inks, an arbitrary figure f appearing in color or as a black, may be incorporated in the design or if de-

35 sired a portion of such figure may be incorporated in one plate and other portions as $f-f'-f''-f'''$ thereof in other plates.

It will be readily understood that there 40 are practically no limitations upon variations in the character of the designs used upon these plates, since the general character of the design may be varied infinitely by

45 changing the adjustments of the rose engine or pantograph, and this design may be modified as desired in the manner above referred to both as to the widths and the relations of the lines, which alone introduces great safety factors in the tints produced by the plates; that an infinite variety

50 of arbitrary figures may be introduced in the body of the design in any or all of the plates, and that any number of colors in any varied relation may be used in connection with the completed safety tint design

55 reproduced from the master printing plates.

After the plates C, D, E and F are completed, a photographic reproduction thereof upon any desired reduced scale is made of each of said plates, great care being required to secure a proper placing of the designs upon the photographic plates. When each plate is developed, the operator has negatives which may be used in making the master plates G, H, I and J corresponding 60 respectively with the metal plates C, D, E

and F, but upon a much reduced scale. By reason of the sharpness and clear definition of the lines upon the plates C, D, E and F and the reduction of this design photographically, all of the lines upon the printing plates G, H, I and J will be sharp, solid and clearly defined, there being no loss in definition during the process by reason of the various photographic steps therein. In fact the definition of these master printing plates will be very much better than in the ordinary photo-engraved master plates made directly from the machine-made negative A.

The plates G, H, I and J are employed 80 to make ordinary transfers as used in planographic printing, such transfers being used to build up a completed design suitable for a particular note or negotiable instrument. The methods employed in making the final 85 printing plates are old and well known in the art of lithography. Each entire plate G, H, I and J may be transferred to the final printing plate, if it be desired to incorporate a medallion design in the safety tint.

If it be desired, instead of reproducing the design upon the plate B four times to secure the plates C, D, E and F, it is apparent that it may be produced twice and each of the 95 reproductions cut in half so that the effects of four distinct color plates may be secured from but two reproductions of the design B. With a tenfold or greater enlargement of the original design, any slight variation in 100 the lines will not be apparent in the final reduced reproduction, so that the plates may be readily cut, any slight condensing of the design due to the loss of metal at the cut being so small as to have absolutely no detectable effect in the finished print.

While I have described the invention with relation to the production of four plates for multicolor work with the arrangement of the lines in four groups, succeeding lines in each group being upon different plates, it is apparent that the same method may be employed in the production of sets of plates of any desired number and any desired grouping of the lines may be followed. For instance, any number of adjacent lines may be included in one plate so long as the lines deleted from the design upon this plate, are included in another or other plates so as to reproduce a completed design. Furthermore, the lines in each plate may be made continuous or may be broken at the intersection of the lines thereon with lines upon other plates. In the former instance, in the final imprint lines of one color will overlay those of another, and difficulties of registration of different plates will be very much reduced.

Also if desired portions of lines may be 130 blocked out so as to have interrupted lines

at certain points in the completed design for purposes of providing means whereby a counterfeit may be distinguished from a genuine note or negotiable instrument.

5. In fact, the manual modification of certain selected lines as to the width or breadth thereof and the selected deletion of lines or portions of lines in one plate and the inclusion of lines or portions of lines in other plates, permits the employment of the same colors in any portion of the imprint and permits different colors to appear in close juxtaposition to each other so as to place the color scheme of the safety tint within 10 the control of the plates, since this wide distribution of colors may be secured if an ink of one color only is employed with relation to each plate. The difficulties of reproduction of a safety tint design made with plates 15 produced by the method or art of my invention, will be more fully appreciated when it is understood that any desired number of colors may be used upon any single plate so that throughout the complete design corresponding lines may appear in a large variety of colors, and even with chromatic effects. 20
- 25

The measure of safety secured by tints made from plates produced in accordance with my invention is increased manifold, due, in part, to the impossibility of mechanically reproducing the geometrical line design forming the tint, and in part to the mechanical difficulties of making plates in accordance with the invention, since such requires highly developed skill in the use of the rose engine or pantograph, in the art of photography, in the use of the brush, in photo-engraving, and in making the imprint, arts so widely divergent as to make counterfeiting extremely difficult, if not impossible.

It is not my intention to limit the invention to the production of sets of plates of any definite number, nor to any limitation as to the selected lines modified or deleted in any plate, and retained in any other plates. Instead of making the enlargement B by the method usually employed in solar or bromide printing, an ordinary camera enlargement may be made.

The method or art of my invention does not utilize any of the methods or practices usually employed in making plates for multi-color work, no color filter screen and no half-tone plates, being employed.

Having described the invention, what I claim as new and desire to have protected by Letters Patent, is:

60. 1. The method or art of making plates for printing safety tints consisting in mechanically creating a line geometrical design, photographically enlarging said design, modifying the characteristics of some lines in said design, whereby such lines are readily 65

distinguishable from the mechanically produced lines, photographically reducing the modified design, and making a photo-engraving of the reduced design.

2. The method or art of making plates for printing safety tints consisting in mechanically creating a line geometrical design, photographically enlarging said design, modifying the characteristics of some lines in said design, whereby such lines are readily distinguishable from the mechanically produced lines, strengthening and removing imperfections in other lines therein, photographically reducing the modified design, and making a photo-engraving of the reduced design. 70
- 75
3. The method or art of making plates for printing safety tints consisting in mechanically creating a line geometrical design, photographically enlarging said design, modifying the characteristics of some lines in said design, whereby such lines are readily distinguishable from the mechanically produced lines, deleting a portion of the design where numbers of lines cross and re-cross each other in close juxtaposition, photographically reducing the modified design, and making a photo-engraving of the reduced design. 80

- 85
4. The method or art of making plates for printing safety tints consisting in mechanically creating a line geometrical design, photographically enlarging said design, modifying the characteristics of some lines in said design, whereby such lines are readily distinguishable from the mechanically produced lines, deleting a portion of the design where numbers of lines cross and re-cross each other in close juxtaposition, substituting an arbitrary design in lieu of the deleted portion, photographically reducing the modified design, and making a photo-engraving of the reduced design. 90
- 95

- 100
5. The method or art of making plates for printing safety tints consisting in mechanically creating a line geometrical design, photographically enlarging said design, modifying the characteristics of some lines in said design, whereby such lines are readily distinguishable from the mechanically produced lines, strengthening and removing imperfections in other lines therein, deleting a portion of the design where numbers of lines cross and re-cross each other in close juxtaposition, photographically reducing the modified design, and making a photo-engraving of the reduced design. 110
- 115

- 120
6. The method or art of making plates for printing safety tints consisting in mechanically creating a line geometrical design, photographically enlarging said design, modifying the characteristics of some lines in said design, whereby such lines are readily distinguishable from the mechanically produced lines, strengthening and removing im- 125
- 130

- perfections in other lines therein, deleting a portion of the design where numbers of lines cross and re-cross each other in close juxtaposition, substituting an arbitrary design in lieu of the deleted portion, photographically reducing the modified design, and making a photo-engraving of the reduced design. 70
7. The method or art of making plates for printing safety tints consisting in mechanically creating a line geometrical design, photographically enlarging said design, modifying the characteristics of some lines in said design, whereby such lines are readily distinguishable from the mechanically produced lines, incorporating an arbitrary figure amongst said lines, photographically reducing the modified design, and making a photo-engraving of the reduced design. 75
8. The method or art of making plates for printing safety tints consisting in mechanically creating a line geometrical design, photographically enlarging said design, whereby a positive reproduction of the design is secured, making a plurality of photographic reproductions of said design upon rigid plates, deleting or blocking out arbitrarily selected adjacent lines in each of said plates, the lines removed in one plate being retained in another plate, photographically 80
- reducing the modified design upon each plate and making a photo-engraved plate from each of said reduced designs, whereby in the use of said last named plates, closely juxtaposed lines of different colors may be produced in the imprint. 85
9. The method or art of making plates for printing safety tints consisting in mechanically creating a line geometrical design, photographically enlarging said design, whereby a positive reproduction of the design is secured, making a plurality of photographic reproductions of said design upon rigid plates, deleting or blocking out arbitrarily selected adjacent lines in each of said plates, the lines removed in one plate being retained in another plate, modifying the width of some of the lines in the designs upon said plates, photographically reducing the modified design upon each plate and making a photo-engraved plate from each of said reduced designs, whereby in the use of said last named plates, closely juxtaposed lines of different colors may be produced in the imprint. 90
10. The method or art of making plates for printing safety tints consisting in mechanically creating a line geometrical design, photographically enlarging said design, whereby a positive reproduction of the design is secured, making a plurality of photographic reproductions of said design upon rigid plates, deleting or blocking out arbitrarily selected adjacent lines in each of said plates, the lines removed in one plate being retained in another plate, strength- 95
- ening and removing imperfections in lines in said plates, photographically reducing the modified design upon each plate and making a photo-engraved plate from each of said reduced designs, whereby in the use of said last named plates, closely juxtaposed lines of different colors may be produced in the imprint. 100
11. The method or art of making plates for printing safety tints consisting in mechanically creating a line geometrical design, photographically enlarging said design, whereby a positive reproduction of the design is secured, making a plurality of photographic reproductions of said design upon rigid plates, deleting or blocking out arbitrarily selected adjacent lines in each of said plates, the lines removed in one plate being retained in another plate, modifying the width of some of the lines in the designs upon said plates, strengthening and removing imperfections in other lines therein, photographically reducing the modified design upon each plate and making a photo-engraved plate from each of said reduced designs, whereby in the use of said last named plates, closely juxtaposed lines of different colors may be produced in the imprint. 105
12. The method or art of making plates for printing safety tints consisting in mechanically creating a line geometrical design, photographically enlarging said design, whereby a positive reproduction of the design is secured, making a plurality of photographic reproductions of said design upon rigid plates, deleting or blocking out arbitrarily selected adjacent lines in each of said plates, the lines removed in one plate being retained in another plate, deleting a portion of the design upon each of said plates, where a number of lines cross and re-cross each other in close juxtaposition, photographically reducing the modified design upon each plate and making a photo-engraved plate from each of said reduced designs, whereby in the use of said last named plates, closely juxtaposed lines of different colors may be produced in the imprint. 110
13. The method or art of making plates for printing safety tints consisting in mechanically creating a line geometrical design, photographically enlarging said design, whereby a positive reproduction of the design is secured, making a plurality of photographic reproductions of said design upon rigid plates, deleting or blocking out arbitrarily selected adjacent lines in each of said plates, the lines removed in one plate being retained in another plate, deleting a portion of the design upon each of said plates, where a number of lines cross and re-cross each other in close juxtaposition, substituting an ar- 115
14. The method or art of making plates for printing safety tints consisting in mechanically creating a line geometrical design, photographically enlarging said design, whereby a positive reproduction of the design is secured, making a plurality of photographic reproductions of said design upon rigid plates, deleting or blocking out arbitrarily selected adjacent lines in each of said plates, the lines removed in one plate being retained in another plate, strength- 120
15. The method or art of making plates for printing safety tints consisting in mechanically creating a line geometrical design, photographically enlarging said design, whereby a positive reproduction of the design is secured, making a plurality of photographic reproductions of said design upon rigid plates, deleting or blocking out arbitrarily selected adjacent lines in each of said plates, the lines removed in one plate being retained in another plate, strength- 125
16. The method or art of making plates for printing safety tints consisting in mechanically creating a line geometrical design, photographically enlarging said design, whereby a positive reproduction of the design is secured, making a plurality of photographic reproductions of said design upon rigid plates, deleting or blocking out arbitrarily selected adjacent lines in each of said plates, the lines removed in one plate being retained in another plate, strength- 130

bitary design in lieu of the deleted portion, photographically reducing the modified design upon each plate and making a photo-engraved plate from each of said 5 reduced designs, whereby in the use of said last named plates, closely juxtaposed lines of different colors may be produced in the imprint.

14. The method or art of making plates for printing safety tints consisting in mechanically creating a line geometrical design, photographically enlarging said design, whereby a positive reproduction of the design is secured, making a plurality 10 of photographic reproductions of said design upon rigid plates, deleting or blocking out arbitrarily selected adjacent lines in each of said plates, the lines removed in one plate being retained in another plate, incorporating an arbitrary figure amongst 15 said lines in one of said plates, photographically reducing the modified design upon each plate and making a photo-engraved plate from each of said reduced 20 designs, whereby in the use of said last named plates, closely juxtaposed lines of different colors may be produced in the imprint.

15. The method or art of making plates for printing safety tints consisting in mechanically creating a line geometrical design, photographically enlarging said design, whereby a positive reproduction of the design is secured, making a plurality of photographic reproductions of said design upon rigid plates, deleting or blocking out arbitrarily selected adjacent lines in each of said plates, the lines removed in one plate being retained in another plate, deleting a portion 30 of the design upon each of said plates, where a number of lines cross and re-cross each other in close juxtaposition, substituting an arbitrary design in lieu of the deleted portion, incorporating an arbitrary 35 figure amongst said lines in one of said plates, photographically reducing the modified design upon each plate and making a photo-engraved plate from each of said reduced designs, whereby in the use of said last named plates, closely juxtaposed lines of different colors may be produced in the imprint.

16. The method or art of making plates for printing safety tints consisting in mechanically creating a line geometrical design, photographically enlarging said design, whereby a positive reproduction of the design is secured, making a plurality of photographic reproductions of said design upon rigid plates, deleting or blocking out arbitrarily selected adjacent lines in each of said plates, the lines removed in one plate being retained in another plate, modifying the width of some of the lines in the design 40 upon said plates, deleting a portion of the 45 signs upon said plates, deleting a portion of

the design upon each of said plates, where a number of lines cross and re-cross each other in close juxtaposition, photographically reducing the modified design upon each plate and making a photo-engraved plate from each of said reduced designs, whereby in the use of said last named plates, closely juxtaposed lines of different colors may be produced in the imprint. 70

17. The method or art of making plates for printing safety tints consisting in mechanically creating a line geometrical design, photographically enlarging said design, whereby a positive reproduction of the design is secured, making a plurality of photographic reproductions of said design upon rigid plates, deleting or blocking out arbitrarily selected adjacent lines in each of said plates, the lines removed in one plate being retained in another plate, modifying the width of some of the lines in the designs upon said plates, deleting a portion of the design upon each of said plates, where a number of lines cross and re-cross each other in close juxtaposition, substituting an arbitrary design in lieu of the deleted portion, photographically reducing the modified design upon each plate and making a photo-engraved plate from each of said reduced designs, whereby in the use of said last named plates, closely juxtaposed lines of different colors may be produced in the imprint. 75 80 85 90 95

18. The method or art of making plates for printing safety tints consisting in mechanically creating a line geometrical design, photographically enlarging said design, whereby a positive reproduction of the design is secured, making a plurality of photographic reproductions of said design upon rigid plates, deleting or blocking out arbitrarily selected adjacent lines in each of said plates, the lines removed in one plate being retained in another plate, modifying the width of some of the lines in the designs upon said plates, incorporating an arbitrary figure amongst said lines in one of said plates, photographically reducing the modified design upon each plate and making a photo-engraved plate from each of said reduced designs, whereby in the use of said last named plates, closely juxtaposed lines of different colors may be produced in the imprint. 100 105 110 115 120

19. The method or art of making plates for printing safety tints consisting in mechanically creating a line geometrical design, photographically enlarging said design, whereby a positive reproduction of the design is secured, making a plurality of photographic reproductions of said design upon rigid plates, deleting or blocking out arbitrarily selected adjacent lines in each of said plates, the lines removed in one plate being retained in another plate, modifying 125 130

the width of some of the lines in the designs upon said plates, deleting a portion of the design upon each of said plates, where a number of lines cross and re-cross each other in close juxtaposition, substituting an arbitrary design in lieu of the deleted portion, incorporating an arbitrary figure amongst said lines in one of said plates, photographically reducing the modified design upon each plate and making a photo-engraved plate from each of said reduced designs, whereby in the use of said last

named plates, closely juxtaposed lines of different colors may be produced in the imprint.

In witness whereof I have hereunto affixed my signature, in the presence of two subscribing witnesses, this 20th day of June, 1921.

DANIEL E. WOODHULL.

Witnesses:

ALFRED S. MAJOR,
F. T. WENTWORTH.
